UNITED STATES PATENT OFFICE

WILLIAM WESTPHAL, OF LOS ANGELES, CALIFORNIA

SEAT CONSTRUCTION FOR FURNITURE

Application filed October 3, 1927. Serial No. 223,679.

This invention relates to seats for chairs and davenport and the like, and more particularly to means for supporting furniture seats whereby a highly resilient and comfortable seat having a spring edge is attained.

An object of my invention is to provide a piece of furniture with a highly resilient seat surface by inexpensive and extremely simple and novel means.

10 Another object is to provide articles of furniture having all the physical attributes above stated which will require, in its construction, only a minimum amount of materials, and a minimum amount of labor.

15 Another object is to provide a novel seat construction for chairs and davenport whereby a highly resilient spring edge seat may be provided without requiring the use of burlap webbing or the usual large number of small springs in the cushion and seat box construction.

20 A further object is to provide a seat of the above character with a minimum number of sturdy inexpensive parts that may be easily and quickly assembled by unskilled workmen.

25 Other objects, advantages and features of invention may appear from the accompanying drawings, the subjoined detail description and the appended claim.

30 The accompanying drawings illustrate the invention in some of the forms I at present deem preferable.

Figure 1 is a perspective view of a chair frame having a seat embodied therein constructed in accordance with my invention.

35 Fig. 2 is a fragmental transverse vertical section taken on line 2-2, Fig. 1.

Fig. 3 is an enlarged fragmentary vertical section taken on line 3-3, Fig. 2, with the padding and covering secured to the chair frame and seat construction.

40 Fig. 4 is a view analogous to Fig. 2 embodying a modification of my invention.

Fig. 5 is a perspective view of a davenport frame having a seat embodying my invention and showing such frame partly covered or upholstered.

45 Fig. 6 is a transverse vertical section taken on line 6-6, Fig. 5.

50 Fig. 7 is an enlarged fragmental vertical

section on the same plane as Fig. 6, showing the forward portion or spring edge of the davenport, with the seat upholstered and a removable cushion on the seat.

In Figures 1-4 inclusive, I have illustrated 65 my invention as applied to a chair having a frame 1, which includes a base or box frame 2, legs 3 on which frame 2 is mounted, a back 4, and arms 5.

My invention comprehends a spring suspended floating seat member 6 mounted for resilient up and down movement in the chair 1. The seat 6 comprises a substantially rectangular seat frame 7 on the lower or upper side of which is secured body supporting 60 means or surface, such as a wire mesh 8 as shown in Figs. 2 and 4 respectively, and to which frame is secured, near the front and rear, respectively, of the seat frame, a pair of slats 9, preferably of metal. The slats extend across the seat frame beyond the sides thereof and are secured at their outer ends to the lower ends of suspension springs 10, the upper ends of which springs 10 are connected to the chair or furniture frame, such 65 as to bars 11 that are secured at their ends to the back 4 and the forward part of the arms 5. The seat frame 7 may be upholstered with upholstering 12 which is supported by the frame and the wire mesh 8. Links 13 extending in parallelism to the sides of the seat frame are pivotally connected at their rear ends to the side edges of the seat frame 7 near the rear of the frame as at 14, while the forward ends of said links are pivotally 70 connected at 15 to the side members 16 of the base frame 2 to prevent material backward and forward movement of the seat in the frame 1. Each of the arms 5 includes a front upright member 22, a top member 23, and a horizontal bar 24 secured at one end 75 to the front member 22 and at its other end to the seat back 4 on the inner side of the arm with its lower edge substantially coincident with the lower edge of the seat frame 80 7 when said frame is in its normal uppermost position as shown in Figs. 1 and 3. A sheet of suitable material, such as strong coarse fabric 40 extends over the top member 23 of each arm 5 and downwardly over the outside 85

90 of each arm 5 and downwardly over the outside 95 100

of a side member 16 of the base frame 2 and over the inside of the lower bar 24 of the arm and the lower edges of said sheet are secured to said side member and said bar respectively forming a space 41 in the arm in which is located the bar 11 and the springs 10 connected thereto. The ends of the seat bars 9 to which said springs are connected extend from the seat under the bar below the space 41. The arms 5 are preferably upholstered with upholstering 17 which extends over the top, outside and inside of the arms over the fabric 40. A cushion 42 may be placed on the seat.

15 The entire surface of the seat 6 including its forward edge 18 yields under the influence of the weight of a person sitting thereon which puts the springs 10 in tension, while the seat is prevented from material sidewise movement in the frame 1 and is maintained with its front edge 18 in alignment with the front of the chair, by means of the links 13. When the seat is depressed by the weight of a person sitting upon it, the springs 10 will 25 not be seen because the seat will not be depressed far enough to expose the springs below the inside arm bars 24. Moreover there is still less chance of the springs being seen when the cushion 42 is placed on the seat 30 which further conceals the springs.

In the modification of my invention shown in Fig. 4 the links 13' are pivoted at their rear ends at 14 to the rear of the seat frame 7 as in Figs. 1-3, but said links are pivoted 35 at 19 near their forward ends to the upright arms of angle brackets 20 which are secured to the inside of the side members of the base frame 2, while the forward ends of said links are connected to the upper ends of springs 21 40 which are connected at their lower ends to the horizontal arms of said angle brackets 20. The springs 21 offer additional resistance to the depression of the rear surface of seat 6 and give additional resiliency to the seat if 45 required.

In Figs. 5-7 I have illustrated my invention as applied to a davenport 25 that includes a base frame 26, legs 27 on which said frame 26 is mounted, a back 28 and arms 29.

50 The seat 30 of the davenport is constructed in accordance with my invention as above described, and comprises a rectangular seat frame 31, to the under side of which are secured longitudinal slats 32 which extend beyond the end of frame 31, a plurality of transverse slats 33 spaced at suitable distances apart that extend slightly beyond the rear of the frame. The ends of the slats 32 are connected to the lower ends of springs 34 which 55 are connected at their upper ends to the davenport frame, such as bars 35 which are located within the arms 29 and are secured at their rear ends to the back 28 and at their forward ends to the forward part of the davenport arms 29. The rear ends of the bars 33 are

connected to the lower ends of springs 36 which are connected at their upper ends to the davenport frame such as the horizontal bar 37 thereof which is secured to, and extends along, the back 28 of the davenport. The forward edge 38 of the seat 30 is resiliently supported upon helical springs 39 which are mounted on the forward member of the davenport base frame 26 and in addition to the suspension springs 34 and 36 give the seat 75 and its forward edge the desired resiliency.

I claim:

In an article of furniture including a frame having a back member; arms mounted on said frame and each including a front upright member and a top member; a horizontal bar secured to the front upright member of each arm and to said back member; bars secured to the front member of each arm and to said back member; a seat; means secured to said seat and extending into the spaces formed in said arms and being underneath said horizontal bars; springs connected at one end to the bars in said arms and at their other end to the means extending into the spaces in said arms; and a covering extending on the inside of said arm from said horizontal bars over the top member and along the outside of said arm and secured to said frame, said springs being adapted to permit downward yielding movement of said seat, and to hold the upper surface of the seat above the lower edge of said horizontal bars when said seat is unoccupied or occupied.

In testimony whereof, I have hereunto set my hand at Los Angeles, California, this 27th day of September, 1927.

WILLIAM WESTPHAL.
